[57] CLAIM

The ornamental design for a combined power strip and electrical cord, as shown and described.

DESCRIPTION

FIG. 1 is a top plan view of a combined power strip and electrical cord showing my new design, the power strip shown separately for clarity of illustration;

FIG. 2 is a side elevational view thereof;

FIG. 3 is an opposite side elevational view thereof;

FIG. 4 is a bottom plan view thereof;

FIG. 5 is an end elevational view thereof;

FIG. 6 is an opposite end elevational view thereof;

FIG. 7 is a perspective view thereof;

FIG. 8 is a top plan view of a second embodiment thereof, the power strip shown separately for clarity of illustration;

FIG. 9 is a side elevational view thereof;

FIG. 10 is an opposite side elevational view thereof;

FIG. 11 is an end elevational view thereof;

FIG. 12 is an opposite end elevational view thereof;

FIG. 13 is a perspective view of a third embodiment thereof;

FIG. 14 is a top plan view thereof, the power strip shown separately for clarity of illustration;

FIG. 15 is a side elevational view thereof;

FIG. 16 is an opposite side elevational view thereof; and,

FIG. 17 is a perspective view of fourth embodiment thereof.

The bottom plan views of the second, third and fourth embodiments are flat and unadorned as shown in FIG. 4.

The side and end elevational views are similar to that of the third embodiment.
